UNITED STATES PATENT OFFICE.

HENRY T. WEIRBACH, OF ALLENTOWN, PENNSYLVANIA, ASSIGNOR OF ONE-HALF TO JOHN M. STEVENS, OF SAME PLACE.

MACHINE FOR TURNING SPIRALS.

SPECIFICATION forming part of Letters Patent No. 358,176, dated February 22, 1887.

Application filed July 22, 1886. Serial No. 208,796. (No model.)

To all whom it may concern:

Be it known that I, HENRY T. WEIRBACH, a citizen of the United States, residing at Allentown, in the county of Lehigh and State of Pennsylvania, have invented a new and useful Improvement in Machines for Turning Spirals, of which the following is a specification.

My invention relates to machines for cutting twist or rope moldings and other forms.

10 The object of my invention is to produce a machine which shall be capable of working both forward and backward, and in which the cutter shall always cut with the grain of the wood, so as to avoid tearing the wood.

15 A further object of the invention is to produce a machine in which the required adjustment of certain parts may be effected with ease and certainty and without necessitating the removal of such parts.

20 To the above purposes my invention consists in certain peculiar and novel features of construction and arrangement, as hereinafter described and claimed.

25 In order that my invention may be fully understood, I will proceed to describe it with reference to the accompanying drawings, in which—

30 Figure 1 is a front elevation of my improved molding-machine. Fig. 2 is a detached view of the cutter-head frame. Fig. 3 is a detached view of the cutter-head. Fig. 4 is a detached view of the division-plate for spacing the twist.

In the said drawings, A designates the bed of the machine, which is supported at its ends 35 by suitable legs or standards, a a', as shown.

B designates the drum, which is mounted horizontally beneath the bed A upon a counter-shaft, b, the bearings of which are in the upper ends of pedestals b', and also in the standards a. 40 b² b³ designate, respectively, a fast and a loose pulley, which are mounted upon the shaft b, contiguous to the standard a, and receive the belt from the line shafting or motor, as required.

45 Upon the outer side of the standard a' is mounted an L-shaped extension-frame, C, in the upper end of which is journaled one end of a shaft, D, the opposite end of said shaft being journaled in the upper part of the said standard a'. The shaft b extends beyond the standard a', and carries two pulleys, b⁴ b⁵, as shown.

Upon the shaft D are mounted a large pulley, d, and a smaller pulley, d', both of which run loosely upon said shaft, the direction of movement of pulley d being opposite to that of pulley d'. These pulleys are driven by suitable belts from the pulleys b⁴ b⁵, the belt from pulley b⁴ to pulley d' being crossed to give the required reverse movement to said pulley d' as compared with the movement of pulley d. d² designates a clutch, which is splined upon shaft D, between the pulleys d d', and the clutch ends of which are moved into engagement with one or the other pulleys d d' upon said shaft D, the hubs of said pulleys being formed with clutch-surfaces upon their inner ends, as shown.

E designates the screw which drives the head-block, as hereinafter described, the said screw extending the full length of bed A upon its front side. Upon one end of this screw is mounted a gear-pinion, e, which meshes with a similar pinion, a², mounted upon a stub-shaft, a³, which projects outward from the upper part of standard a'. This pinion a² meshes in turn with a pinion, d³, which is mounted rigidly upon the shaft D.

The clutch d² is operated by a shipper-bar, d⁴, which is pivoted at its lower end to a supporting-bar, a⁴, extending outwardly from the standard a'. To the upper end of the shipper-bar d⁴ is pivoted one end of a rod, d⁵, which extends longitudinally across the front of the bed A, being supported by and sliding in bangers d⁶, and upon this rod are placed stops d⁷, which are clamped thereto by set-screws, and are thus capable of being slid longitudinally thereon and secured at any desired point. The carriage H, as it is reciprocated on the bed A, as hereinafter described, strikes one of these stops at the end of each movement, moves the rod d⁵, and operates the shipper-bar d⁴, and throws the clutch d² out of engagement with one and into engagement with the other pulley, d or d', on the shaft D, as the case may be.

From the above description it will be seen that when the clutch is moved into engagement with the larger pulley, d, the screw E will be rotated in one direction, while when the clutch is shifted into engagement with the smaller pulley, d', the screw E will be rotated in the opposite direction and at a greater

speed than that imparted by the larger pulley, *d*. The larger pulley drives the screw during the operation of cutting, while the smaller pulley reverses the screw in order to bring the head-block back to the starting-point.

F designates the head-stock, *G* the tail-stock, and *H* the carriage for the head-block or frame *I*. These several parts, excepting the head-stock, slide longitudinally of the bed *A* in suitable guides thereon in the usual or any preferred manner, the carriage *H* having a nut, *h*, which embraces the screw *E*, and by means of which the carriage is fed up to its work.

15 The shaft *f* of the head-stock carries the usual chuck, *f'*, at its front end, and at its rear end said shaft carries a large gear-wheel, *f''*, which meshes at times with a gear-pinion, *a'*, and also with a gear-pinion, *a*, the latter being driven by a gear-pinion, *e*, upon the corresponding end of screw *E*. The gear-wheel *f''* is mounted loosely upon the head-stock shaft *f*, and is connected by a pin, *f³*, with the division-plate *f⁴*, which is also loosely mounted upon said shaft *f*. *f⁵* designates an arm, which is rigidly mounted upon shaft *f* so as to turn therewith, said arm extending radially outward from shaft in front of the division-plate *f⁴*. At its outer end the arm *f⁵* carries a spring-bar, *f⁶*, which is pivotally connected to the arm *f⁵* at one end, and at the other end carries a pin, *f⁷*, by which said bar is connected to the division-plate *f⁴* in the following manner: This division-plate is provided on its front face 30 with six concentric annular grooves, *f⁸*. The first or inner groove is blank; the second groove is provided with two holes *f⁹*; the third groove with three holes, and so on to the sixth or outer groove, which has six holes *f⁹*, the 35 said holes in all of the grooves being equidistant, as shown. By virtue of this arrangement the position of the piece of wood to be cut can be varied relative to the cutter in the head-block, so as to properly space the twist by placing the pin *f⁷* in one or another of the holes *f⁹*. By forming the division-plate with a number of grooves each having its set of apertures the most delicate adjustment can be 40 obtained in spacing the beads to be cut.

45 The centering-spindle *g* of the tail-stock *G* is adjusted longitudinally in said stock by means of a screw, *g'*, passing through an extension, *g''*, of said spindle and working in the frame *g³* of the stock, said screw being operated by a hand-wheel, *g⁴*, as shown.

50 *I* designates the cutter-head frame, which is moved laterally in suitable slides upon the carriage *H* by a screw, *h'*, so as to bring the cutters properly up to their work.

55 *i* designates the cutter-shaft, which is suitably journaled in frame *I*, and which carries a pulley, *i'*, at its rear end, a belt, *j*, running over said pulley and under the drum *B*, to drive the cutter-shaft.

K designates the cutter-head, which is a 65 rectangular block having a socket, *k'*, in one end to receive the front end of the cutter-shaft, and having its opposite end cut away on its upper side and a movable block, *k*, adjustably secured thereon by means of a set-screw, *k²*, by means of which it is clamped down upon the cutter. A set-screw, *k³*, serves to clamp the cutter-head to its shaft *i*, and the set-screw *k⁴* serves, as stated, to hold the clamping-block *k* firmly down upon the cutter, holding the cutter firmly in its operative position. The form of the cutter will vary according to the work to be done, and in any given instance may be of the usual or any preferred style. 80

It will thus be seen that the machine is simple and durable in construction and capable of operating in either direction, as desired. The adjustments mentioned in the foregoing description can all be easily and rapidly made 85 without necessitating the removal of any of the parts involved in such adjustments.

Having thus described my invention, what I claim as new, and desire to secure by Letters Patent, is— 90

1. The combination, with the cutter-head shaft, of the cutter-head *K*, circular in cross-section, formed with the central longitudinal socket *k'* in one of its ends, and having its other end cut away on its upper side, as 95 shown, to form the shoulder, the set-screw *k²*, extending into the said socket, the clamping-block *k*, and the set-screw *k³*, for adjusting the said block, as set forth.

2. The combination, with the main bed-frame, of the drive-shaft carrying the pulleys at each end, the head-block, the screw operating the same and carrying a pinion at each of its ends, the clutch-shaft provided with the pinion and the clutch mechanism and having 105 the pulleys loosely mounted upon it, the intermediate pinion, the head-stock shaft carrying the loosely-mounted gear-wheel, and the loosely-mounted division-plate connected to and turning with the said gear-wheel and 110 formed with a series of grooves and equidistant apertures, the fixed arm, the spring-bar pivoted to the arm at its outer end, and provided with the end pin engaging with one of the said apertures, and the pinions interposed 115 between the gear-wheel and the pinion on that end of the operating-screw, substantially as described, for the purpose set forth.

In testimony that I claim the foregoing as my own I have hereto affixed my signature in 120 presence of two witnesses.

HENRY T. WEIRBACH.
